FILM UNWINDING MECHANISM

Norman McKay Holme-Shaw,
Frankenmuth, Mich.

Application July 24, 1950, Serial No. 175,577

2 Claims. (Cl. 271—2.17)

1

This invention relates to film supporting mechanism and more especially to a mechanism on which a roll of reversely wound film may be placed, and from which it may be progressively drawn and fed to a conventional motion picture projector, without the necessity of rewinding as is at present necessary.

One of the prime objects of the invention is to design a very simple, practical, neat-appearing standard and film plate on which a reversely wound strip of film may be placed, and from which it may be readily uncoiled as it is fed to a conventional projector without rewinding, thus conserving time, unnecessary strains and wear and tear on the film.

Another object is to provide a standard and inclined film plate on which the film is removably mounted, and from which it is unwound as the film is fed to the projector.

A further object is to provide a mechanism including an inclined film plate of flat, disk-like form, having a centrally disposed pin on which a relatively heavy conical-shaped knob member is releasably mounted, so that the inner periphery of the wound film engages therewith with friction sufficient to rotate said plate as the film is unwound and drawn through the projector.

Still a further object is to provide an anti-friction, easy operating film plate and mechanism, which can be placed directly in the rear of a conventional projector and from which wound film may be drawn as the projector is operated.

With the above and other objects in view, the present invention consists in the combination and arrangement of parts, hereinafter more fully described, illustrated in the accompanying drawing, and more particularly pointed out in the appended claims, it being understood that changes may be made in the form, size, proportion, and minor details of construction, without departing from the spirit or sacrificing any of the advantages of the invention.

In the drawing:

Fig. 1 is an edge-elevational view of my new film supporting mechanism, the film being shown in section.

Fig. 2 is a front-elevational view thereof.

Fig. 3 is an enlarged, fragmentary section of the film plate and pin showing the conical knob arranged in position thereon.

Fig. 4 is a transverse-sectional, plan view of the conical knob taken on the line 4—4 of Fig. 1.

Referring now more specifically to the drawing in which I have shown the preferred embodiment of my invention, the mechanism in general

2

is indicated at S and comprises a relatively heavy base 5 formed of any desired material with a curved, upwardly projecting arm 6 secured thereto and terminating in a housing 7 in which an anti-friction bearing is mounted, said housing being disposed at an angle with relation to a horizontal line, and is bored to accommodate anti-friction bearings 8 in which the film plate shaft 9, provided on the lower face of the film plate 10, is mounted.

The film plate 10 is preferably formed with a hub 10a in which the shaft 9 is mounted, and is disposed at right angles to the shaft 9 as shown, said shaft projecting through the film plate and the upper end is split as at 11 and for a purpose to be presently described.

A conical shaped knob member 12 is mounted on the split section 11 of the shaft 9, and this knob is relatively heavy, being centrally bored as at 13, and a transversely disposed pin 14 spans said bore, said pin being releasably accommodated in the split section 11 of the shaft 9 when the knob is mounted in position, so that the knob rotates with the film plate but is freely removable when desired.

When a strip of film F is fed through a projector (not shown) it is reversely wound on a conventional reel (not shown), and for the present purpose the reel is vertically separable so that the wound film may be removed without unwinding; after removal from the reel the wound or coiled film is then placed on the film plate 10 over the split section 11 of the shaft, after which the knob 12 is placed in position with pin 14 in engagement with the section 11, the lower end of the knob 12 being inserted through the opening in the coil, so that the inner periphery of the wound film bears thereon.

It will be noted that the one end of the housing 7 is shouldered as at 15 to engage the hub 10a and the bearings 8 minimize friction.

In operation, the inner free end G of the coiled film F is threaded in the projector (not shown), and as the projector is operated, the film plate 10 is rotated and progressively unwinds the film, said plate being freely revolvable with a minimum of friction or resistance. The contact of the film with the outer conical face of the knob is at the one edge only, so that there is a limited adherence or clinging action, and there is no tendency to form a tighter coil or slide the convolutions on each other. The film guides on the conical surface of the knob as it leaves the coil and the knob is movable axially on the shaft in response to excessive tension on the film. Thus, the knob moves axially in response to excessive

unwinding tension and undue strains which might break the film are not placed thereon.

The fact that it is unnecessary to rewind the film preserves and insures longer life with a much better reproduction, because of absence of scratches, abrasions and marring produced by usual rewinding.

From the foregoing, it will be appreciated that I have designed an apparatus that eliminates film rewinding, protects from damaging tension, 10 surface scratches and abrasions, and provides clearer film over a much longer span of time.

What I claim is:

1. A motion picture film strip unwinding apparatus comprising a base having an upwardly 15 extending, angularly disposed housing, a shaft journaled in and projecting from the upper end of said housing, the projecting end section of said shaft being bifurcated, a substantially flat film disc fixed on said shaft below said bifurcated section and disposed at substantially right angles to said shaft for supporting a roll of reversely coiled film on the disc with the shaft projecting through the central opening in the coiled roll, a relatively heavy, inversely disposed, conical 20 knob having a central bore removably mounted on said shaft, said knob having a pin spanning said bore and adapted to seat in the bifurcated end of said shaft and prevent rotation of said knob on said shaft while allowing relative axial movement of said knob thereon in response to excessive tension on the unwinding film, the lower end of said knob extending through the central opening in the coiled roll to maintain

the roll in position and permitting unwinding of the film from the inner periphery of said roll.

2. A motion picture film strip unwinding apparatus comprising a base having an upwardly extending housing, a shaft journaled in and projecting from the upper end of said housing, a film disc fixed in said shaft at substantially right angles thereto for supporting a roll of reversely coiled film on the disc with the shaft projecting through the opening in the coiled roll, a relatively heavy, inversely disposed, conical knob having an axially extending bore mounted on said shaft, means preventing rotation of said knob on said shaft while permitting relative axial movement of said knob in response to excessive tension on the unwinding film, the lower end of said knob extending through the opening in the roll to maintain the roll in position and permit unwinding of the film from the inner periphery of the roll.
